CONSTRUCTION AND METHOD OF ANCHOR-
ING SHOE CLEATS

John T. Riddell, Chicago, Ill.

Application August 14, 1939, Serial No. 290,113

8 Claims. (Cl. 12—142)

This invention relates to detachable shoe cleats, such as football cleats and the like, made of molded pliable material and particularly to improvement in the method of securing such cleats onto the sole of a shoe.

The main objects of this invention are to provide an improved method of fastening detachable cleats onto shoe soles; to provide such a method whereby, in a simple fashion, a double locking or gripping effect is had between the cleat and the shoe sole; and to provide an improved method of attaching detachable cleats to a shoe sole which obviates danger of the cleat working loose from the shoe sole so as to become weakened and pull off from the securing stud and yet permits the cleat to be readily detached when such is desired.

A specific embodiment of this invention is shown in the accompanying drawing, in which:

Figure 1 is a sectional view of a detachable cleat for practicing the improved method of fastening the same to a shoe sole.

Fig. 2 is a sectional view of the socket means provided in a shoe sole for attaching the cleat thereto in accordance with the improved method, and,

Fig. 3 is a sectional view of the cleat attached to the shoe sole according to the improved method.

In the form shown in the drawing, the improved cleat comprises a body 1 made of a pliable resilient material, such as rubber, having molded thereto a securing stud comprising a cylindrical body 2 having a threaded shank 3 projecting axially therefrom and from the cleat body, a plurality of radially projecting prongs 4 on the opposite end of the securing member body 2 and an annular collar 5 surrounding the securing member body 2 and forming a head adjacent the end from which the radially extending prongs 4 project.

As shown in Fig. 1, the reduced diameter of the shank 3 provides a shoulder 6 at the shank end of the securing member body 2 and the securing member is so positioned in the cleat 1 that the shoulder 6 is disposed below, or recessed into, the sole-engaging surface 7 of the cleat 1, leaving a recess 8 between the end 7 of the cleat and the shank 3.

The head 5 provides a second shoulder 9 within the body of the cleat 1 which shoulder is completely surrounded by the material of the cleat 1 so as to provide a compression member acting on the cleat material between the shoulder 9 and the end 7 of the cleat when the cleat is

fastened onto a shoe sole. The prongs 4 are formed by splitting, sawing or otherwise dividing the inner end of the cylindrical body 2 beyond the annular collar 5 and then turning the posts or sections thus formed outwardly by means of a suitable tool or die. The construction of this cleat is more fully described in my copending application, Serial No. 290,444, filed August 16, 1939.

As shown in Fig. 2, the socket member for holding the cleat shown in Fig. 1 onto the shoe sole comprises an internally threaded tubular member 10 having an annular flange 11 at one end, the tubular member being set into a suitable aperture in the shoe sole 12 with the flanged end on the inner side of the sole where the flange 11 becomes embedded into the sole material when the tubular member is secured thereto. The opposite end of the tubular member 10 projects outwardly beyond the bottom surface of the sole 12 and a wash 13 is set over the projecting end and is secured against the bottom surface of the sole by rolling or otherwise turning under the projecting portion to form a locking bead or rim 14 which bears against the washer 13 and holds the same tightly in place against the sole. As shown in Fig. 2, the washer 13 may be provided with axially extending prongs 15 which become embedded in the sole 12 to lock the washer against the possibility of angular turning relative to the axis of the tubular member or socket 10.

As shown in Fig. 3, the cleat illustrated in Fig. 1 is secured to the shoe sole by merely threading the shank 3 of the cleat securing member into the internally threaded socket on tubular member 10, which has been previously affixed onto the shoe sole, and then turning the cleat tightly down against the shoe sole or the washer 13 until the cleat becomes rigidly secured onto the sole.

During the process of attaching the cleat to the shoe sole several conditions are brought about by which my improved fastening method is accomplished, and the cleat itself is particularly designed to bring about these conditions which are first, the accomplishment of a combined frictional and compression lock between the end 7 of the cleat 1 and the shoe sole or the washer 13, and second, a positive metal to metal bind between the shoulder 6 on the cleat securing member 2, and the rolled rim or bead 14 at the projecting end of the socket or tubular member 10.

The first feature; namely, the combined fric-

tion and compression lock between the pliable cleat material and the shoe sole and the washer 13 is brought about by the fact that the recess 3 in the sole engaging end of the cleat body is of greater depth than the distance to which the rolled end 14 of the tubular member 10 projects beyond the surface of the washer 13, thereby causing the end portion 7 of the cleat body to be compressed, as indicated at 16 in Fig. 3, when 10 the cleat is drawn up tightly against the washer 13, the shoulder 9 on the annular collar 5 of the cleat securing member serving to prevent the cleat being pulled off from the securing member and to cause compression of the material between the shoulder 9 and the washer 13, thus 15 bringing about a condition whereby the securing member 2 is constantly under tension relative to the tubular socket 10 and the shoe sole and whereby a maximum frictional grip between the 20 pliable material of the cleat and the washer 13 is had.

The second feature; namely, the metal to metal bind between the rolled rim or bead 14 of the socket 10 and the shoulder 6 at the shank 25 end of the securing member 2 provides two definite results which are first, the positive metal to metal bind between the shoulder 6 of the securing member 2 and the rim or bead 14 of the socket member 10 which further serves to prevent 30 inadvertent turning of the cleat relative to the socket member and the shoe sole, and second, this feature provides a positive stop which prevents the flange-engaging end 7 of the cleat from becoming too much compressed, and 35 thereby spread outwardly, and also prevents the securing member 2 from being pulled out of the cleat 1 by too great an application of twisting force during the application of the cleat to the shoe sole.

40 It will now be seen that my improved method of securing a cleat onto a shoe sole consists in compressing the sole or washer engaging end of the cleat to provide a combined friction and compression lock between the cleat and the washer and then causing a positive metal to metal compression bind between the cleat securing member and the socket into which it is threaded so as to not only provide an additional locking means for the cleat when it is mounted 45 on the shoe sole, but also to limit the amount that the washer engaging end of the cleat can be compressed during the application.

The main advantages of my improved method 50 of fastening shoe cleats reside in the more perfect and secure locking engagement that is obtained between the detachable cleat and the sole on which it is mounted, and the fact that the improved method obviates the danger of the cleat working loose on the shoe sole, during the 55 severe usage to which such cleats are subjected, so that the cleat cannot be twisted or pulled loose from its securing stud.

Other advantages reside in the simplified structure of the cleat and its securing means that 60 is permitted by the use of the improved cleat fastening method.

It will be understood that certain of the method steps herein described and illustrated may be altered or omitted without departing from the spirit of this invention as defined by the following claims.

I claim:

1. The method of anchoring a cleat to the sole of a shoe which consists in fixing an internally threaded socket member in the shoe sole, pro-

viding a cleat of pliable resilient material having an end bearing surface and a threaded stud fixed therein and projecting therefrom, screwing said stud into said socket until said end-bearing surface substantially engages said sole or socket member and then further screwing said stud into said socket member to compress the pliable cleat material at said end-bearing surface and locking the stud threads by the engagement of limit stop-bearings on said socket member and 10 stud.

2. The method of anchoring a cleat to the sole of a shoe which consists in fixing an internally threaded socket member in the shoe sole, providing a cleat of pliable resilient material 15 having an end-bearing surface and a threaded stud fixed therein and projecting from a recess surrounding said stud in said bearing surface, screwing said stud into said socket until said cleat end-bearing surface substantially engages 20 said sole or socket member and then further screwing said stud into said socket member to compress the pliable cleat material and bring a shoulder on said stud into thread-locking engagement with said socket.

25 3. The method of anchoring a cleat to the sole of a shoe which consists in fixing an internally threaded socket member in the shoe sole, providing a cleat of pliable resilient material having and end-bearing surface and a threaded stud 30 fixed therein and projecting from a recess there-in surrounding said stud, and said stud having a projecting annular shoulder in said recess below the said end-bearing surface, screwing said stud into said socket until said end-bearing surface substantially engages said sole or socket 35 member and then further screwing said stud into said socket to compress the pliable cleat material and bring said shoulder into thread locking engagement with said socket member.

40 4. The method of anchoring a cleat to a shoe sole which consists in fixing in the shoe sole an internally threaded socket member having a rim projecting beyond the bottom sole surface, providing a cleat of pliable material having an end-bearing surface and a threaded stud fixed there-in and projecting therefrom, and having an annularly projecting shoulder recessed in and below said cleat end-bearing surface, screwing said stud into said socket until said cleat end-bearing 45 surface substantially engages said sole or socket member and then further screwing said stud into said socket to compress the pliable cleat material at said end and tightly engage said stud shoulder with said socket rim.

55 5. The method of anchoring a cleat to a shoe sole which consists in fixing in the shoe sole an internally threaded socket having a rim projecting beyond the bottom sole surface, providing a cleat of pliable material having an end-bearing surface and having a threaded stud fixed therein and projecting therefrom, and having a projecting shoulder recessed in and below said cleat end-bearing surface at a greater distance than the projecting height of said socket rim, 60 screwing said stud into said socket until said cleat end substantially engages said sole or socket member, and then further screwing said stud into said socket member to tightly engage said stud shoulder with said socket rim after 65 compressing the pliable cleat material at said bearing end.

70 6. The method of anchoring a cleat to a shoe sole which consists in providing an internally threaded socket fixed in the shoe sole and hav-

- ing a rim projecting beyond the bottom sole surface and a washer disposed against the shoe sole and secured by said rim, providing a cleat of pliable material having an end-bearing surface 5 and a threaded stud fixed therein and projecting therefrom, said stud having a projecting shoulder recessed in and below said cleat end-bearing surface, screwing said stud into said socket until said cleat end substantially engages 10 said washer, and then further screwing said stud into said socket member to tightly engage said stud shoulder with said socket rim after compressing the pliable cleat material at said bearing end.
- 15 7. The method of anchoring a cleat to a shoe sole which consists in fixing in the shoe sole an internally threaded socket having a rim projecting beyond the bottom sole surface, and having a washer disposed against the shoe sole and secured by said rim, providing a cleat of pliable material having an end-bearing surface and a 20 threaded stud fixed therein and projecting therefrom and having a projecting shoulder recessed in and below said cleat end-bearing surface at a greater distance than the projecting height of 25 said socket rim, screwing said stud into said

socket until said end-bearing surface substantially engages said washer, and then further screwing said stud into said socket to tightly engage said stud shoulder with said socket rim after compressing the pliable cleat material at 5 said end-bearing surface.

8. In a shoe, a cleat of pliable material having a molded-in stud comprising a body portion embedded in the cleat, a threaded shank projecting from said body portion and beyond one end of 10 the cleat, said one end of said cleat having a recess therein around said shank and leading to said body portion, said shank being of smaller cross-section than said body portion and recess, and said body portion having an enlarged head 15 within the cleat, and a threaded socket member fixed in the shoe sole and having a rim projecting beyond the bottom sole surface a less distance than the depth of said recess, whereby when said shank is screwed into said socket member until said stud body engages said socket rim, the cleat material will be compressed at the end from which said shank projects.

JOHN T. RIDDELL. 25
